UNITED STATES PATENT OFFICE.

JAMES S. ARCUS, OF CHICAGO, ILLINOIS.

CHECK HOLDER AND NOTCHING DEVICE.

1,368,995.

Specification of Letters Patent. Patented Feb. 22, 1921.

Application filed December 1, 1917. Serial No. 204,862.

To all whom it may concern:

Be it known that I, JAMES S. ARCUS, a citizen of the United States, and a resident of Chicago, in the county of Cook and State 5 of Illinois, have invented certain new and useful Improvements in Check Holder and Notching Devices; and I do hereby declare that the following is a full, clear, and exact description thereof, reference being had to 10 the accompanying drawings, and to the characters of reference marked thereon, which form a part of this specification.

This invention relates to a novel holder and notching device for sales checks, such 15 as are used in restaurants, at soda fountains and like places to indicate on the check the price of the commodity or merchandise bought by the customer.

Among the purposes of the invention are 20 to provide a simple, economical and readily manipulated device for this purpose by which to hold a book of sales checks and to otherwise improve devices of this character.

Another object of the invention is to improve 25 the shearing action between the shearing edges of the notching device.

A further object of the invention is to provide a novel form of sales holding and notching device in which the device carries a receptacle 30 to receive punchings or parts detached from the checks by the shearing or tearing-off device.

The invention consists in the combination and arrangement of the parts shown in the 35 drawings and described in the specification, and is pointed out in the appended claims.

Figure 1 is a perspective view of a holder and notching device embodying my invention.

40 Fig. 2 is a longitudinal section thereof.

Fig. 3 is a plan view of the front end of the device.

Fig. 4 is an end view thereof.

Fig. 5 is a partial plan view of the blank 45 from which the device is made.

Fig. 6 is an edge elevation of a modified form of the device.

Fig. 7 is a section on the line 7—7 of Fig. 3.

50 The holder is made of a single elongated sheet metal plate and comprises a body portion 10 of a width substantially equal to the width of the checks supported thereby, the checks being indicated in dotted lines in Fig. 1. At one end of the plate it is turned

back upon itself to form clamping jaws 11, 12. The resiliency of the metal from which the device is made is relied upon to clamp or hold a book of checks in the holder. In the present instance the clamping engagement is that between the free end of the upper jaw and a corresponding portion of the lower jaw; but this resilient engagement may be effected by other forms of the clamping members. Preferably the free end of the upper jaw and the corresponding part of the plate at the lower jaw are turned inwardly toward each other to form teeth or spurs 14 to engage into the stubs of the book of sales checks and thereby effect a better hold of the device on the book of checks.

At the end of the plate remote from the clamping jaws said plate is cut away between its side edges to provide an elongated notching tongue 15. This tongue is left integral at its rear end 16 with the plate. At its forward end the tongue is shaped to provide a notching point 17. The free end of the tongue is raised away or spaced from the front or upper face of the plate 10 to afford a space between the tongue and plate to receive the edge of a check to be notched or punched. Said free end of the tongue is given a tendency to thus space itself from the plate but, by reason of its resiliency is forcible toward the plate.

The free or notching end of the tongue may function to constitute either a shearing point or a tearing point. As a shearing point the edges of the tongue, at the sides of the extreme point, coöperate with corresponding edges 18, 18 in the V shaped notch of the plate from which a portion of the tongue was cut, so as to shear a triangular piece from the edge of a check. The opening in the plate from which the tongue is cut is preferably widened back of the shearing or tearing edge so as to afford a clearance for the detached pieces of the checks to fall through said opening.

When the tongue is designed as a shearing or cutting member the free or pointed end thereof is preferably turned obliquely toward the shearing edges 18 on the plate so as to effect a better shearing coaction of the tongue and plate edges. When this is done the extreme point of the tongue is slightly shifted backwardly from the extremity of the V shaped notch, and it becomes desirable to deform the plate in advance of the V

100

105

110

shaped notch therein so as to bring the cutting or shearing edges of the tongue and plate into proper shearing relation. This may be effected by swaging the plate downwardly or rearwardly in line with the point of the V shaped notch, as indicated at 20. The effect of this swaging operation is to slightly draw together the shearing edges of the plate so as to properly coöperate with the shearing edges of the tongue, and to also bring the shearing edges 18 of the plate in planes oblique to the planes of the shearing edges of the tongue, as indicated in Fig. 7. By so doing the upper angles of said shearing edges 18 are presented to the shearing edges of the tongue in the most effective way for shearing action.

The tongue 15 is provided in rear of the notching point thereof with an inturned lug 20 which constitutes a gage stop to limit the movement of the sales checks or slips into the space between the tearing tongue and plate and thereby limit the depth of the notch.

In order that the pieces detached from the checks may not fall indiscriminately about, a receptacle 23 may be provided to receive them as they are cut or torn from said check. In the present instance such a receptacle is located on the rear side of the plate 10 opposite to the notching tongue. It is preferably made integral with said plate. This may be conveniently effected by forming one end of the blank of which the holder is made with lateral wings 24, 24 to constitute, when folded, the side walls of the receptacle, and with a longitudinal extension 25, that, when folded backwardly on the plate 10 along the fold lines indicated in Fig. 5, constitutes the bottom, front and rear walls 26, 27 and 28, respectively, of said receptacle. One of said walls, as the rear wall 28, may be provided with an opening 29 (Figs. 2 and 5) through which the pieces of the checks may be emptied from the receptacle.

In Fig. 6 is shown a modification wherein in the receptacle 23 is omitted. In said modification the plate 30, the jaws 31, 32, 50 the spurs 34, the tongue 35 and the gage stop 36 are the same as the like parts before described. In the construction shown in Fig. 6, however, the end of the plate is elongated at 40 beyond the notching tongue 55 a distance to give suitable support against which the shearing edges of the notching tongue act. Said end of the plate may, however, be otherwise strengthened. The extended end of the plate is deformed at 41 60 in the manner before described to properly present the shearing edges of the plate to the shearing edges of the tongue.

The notching or punching device may be employed for uses where the holding device is not required, and in this respect cer-

tain of the claims are not limited to a holding and notching device.

What I claim as my invention is:

1. A combined sales check holder and price-marking device comprising a support 70 having at one end means to confine a book of checks, and having at its other end on the check-supporting side of the device a shearing marking device, embracing shearing edges on the device outwardly beyond 75 the end of a book of checks supported thereon, and a resilient member on the check-supporting side of the device normally spaced from, and provided with shearing edges movable toward and away from, said 80 first shearing edge.

2. A sales check holder and price marking device comprising an elongated support having at one end means for confining a book of checks, said support comprising, 85 at its other end a fixed shearing member and a movable shearing member, the free end of which latter extends longitudinally of the support and is movable toward and from the fixed shearing member by pressure applied through a book of checks mounted on said support, and a receptacle at the latter end of the support to receive pieces cut from the checks by said shearing 95 means.

3. A sales check holder and marking device comprising a support having at one end confining means for an end bound book of checks and at its other end marking means, embracing converging fixed and 100 movable shearing edges on the check supporting side of said support, the fixed edges bounding an aperture in the support beyond the free ends of the checks, and the movable shearing edge being formed on a 105 member that extends toward but terminates short of the apertured end of the support and movable toward and from said fixed shearing edges, and a receptacle at the end 110 of said support in position to receive pieces detached from the checks.

4. A sales check holder and marking device comprising an elongated support having at one end check pad holding means, and near its other end a perforation having 115 shearing edges, and a resilient tongue extending toward, but terminating short of the latter end of said support, and formed at its free end with a point spaced from, and springable toward and from, the apertured end of the support and having shearing edges, said free end of the tongue and support being relatively deformed to present their shearing edges in an oblique shearing plane.

5. A sales check holder and marking device comprising an elongated support, having at one end means to hold a sales check book and at its other end, outwardly beyond a pad of checks supported thereon a shear- 130

ing notch, said support comprising a main member and a springable member to support said pad, with the springable member having a shearing end formation outwardly beyond the end of the pad to coöperate with said shearing notch, whereby pressure to bring the shearing elements into shearing relation can be exerted through said pad of checks, and a receptacle at the free end of 10 the support to receive pieces detached from said checks.

6. A sales check holder and marking device comprising an elongated support for a pad of checks, one end of which is equipped with holding means for said pad, and the other end of which is adapted to extend beyond the free end of the pad and is equipped with a shearing edge formation, there being a longitudinally disposed spring- 20 able shear ended tongue extending toward, but terminating short of, and normally spaced from, but movable at its shear end toward, said shearing edge formation, and a receptacle at the free end of the support at 25 said shearing edge formation to receive pieces sheared from a detached check.

7. A sales check holder and notching device made of a single plate of resilient material, one end of which is shaped to provide 30 resilient check holding jaws, and a notching tongue at the other end of said plate, the said plate at the latter end thereof being formed to provide wings which are folded backwardly against the plate to constitute 35 a receptacle to receive cuttings from the checks.

8. In a check holding and notching device a plate cut away within its edges to provide a notching tongue, one end of the 40 tongue being pointed and provided with shearing edges, the plate being provided with coöperating shearing edges, said plate being deformed beyond the point of the tongue to bring the faces of the shearing 45 edges of the plate in planes oblique to the planes of the faces of the shearing edges of the tongue.

9. A device for the purposes set forth comprising a support and a notching tongue, the latter pointed at one extremity and provided at the sides of its point with shearing edges and the support being provided with 50 shearing edges whose faces bear oblique

relation to the faces of the tongue shearing edges.

10. A sales check holder and marking device comprising a support having at one end check book holding means, the other end of said support being provided with a notching tongue, the free end of which, near the latter end of the support, is pointed and spaced from said support, said support and the pointed end of the tongue having co-acting shearing edges, and the support beyond the point of said tongue being centrally swaged to shift the shearing edges thereof toward each other and to present the faces of the support shearing edges obliquely to the faces of the tongue shearing edges.

11. A sales check holder and marking device comprising an elongated support provided at one end with a holding device for a tab of checks, and outwardly beyond said holding device toward the other end of 75 said support with a longitudinally disposed elongated tongue extending toward said latter end, the support and tongue having co-operating relatively convergingly angled shearing edges to notch a detached check inserted therebetween, and a check limiting stop in rear of the shearing end of said tongue.

12. A sales check holder and marking device comprising a support including two 85 members of unequal length, both extending in the same direction as a tab of checks adapted to be supported thereby, one of which said members is resilient and spaced from the other to permit movement of one 90 relative to the other, the longer one of said members having a sharpened edge perforation and the shorter member having a shearing portion adapted, upon an approach of said members, one toward the other, to shear 95 the margin of a check interposed between them, and a receptacle carried on the longer member and arranged to receive cuttings from the checks.

In testimony whereof I affix my signature 10 in the presence of two witnesses this 19th day of November, 1917.

JAMES S. ARCUS.
